L. SCHLEPP.
ELECTRIC CANDLE STAND.
APPLICATION FILED AUG. 26, 1919.

1,331,385.

Patented Feb. 17, 1920.

UNITED STATES PATENT OFFICE.

LOUIS SCHLEPP, OF BROOKLYN, NEW YORK.

ELECTRIC-CANDLE STAND.

1,331,385.

Specification of Letters Patent. Patented Feb. 17, 1920.

Application filed August 26, 1919. Serial No. 319,861.

To all whom it may concern:

Be it known that I, LOUIS SCHLEPP, a citizen of the United States, and a resident of the city of New York, borough of Brooklyn, in the county of Kings and State of New York, have invented a new and Improved Electric-Candle Stand, of which the following is a full, clear, and exact description.

10 The object of the invention is to provide a new and improved electric candle stand arranged to permit convenient adjustment with a view to hold the electric lamp in proper position relative to the surrounding 15 body member. Another object is to permit of conveniently attaching the stand at its base to a suitable support and at the upper end to the usual socket of an electric lamp.

With these and other objects in view, the 20 invention consists of certain novel features of construction, as hereinafter shown and described and then specifically pointed out in the claims.

A practical embodiment of the invention 25 is represented in the accompanying drawings forming a part of this specification, in which similar characters of reference indicate corresponding parts in all the views.

Figure 1 is a side elevation of an electric 30 lamp fixture provided with the improved candle stand;

Fig. 2 is a sectional side elevation of the electric candle stand;

Fig. 3 is a side elevation of the electric 35 candle stand;

Fig. 4 is a cross section of the same;

Fig. 5 is a sectional plan view of the same on the line 5—5 of Fig. 3;

Fig. 6 is a side elevation of the modified 40 form of the candle stand; and

Fig. 7 is a sectional plan view of the same on the line 7—7 of Fig. 6.

The electric candle stand in its general construction comprises a bar 10 provided at 45 its lower and upper ends with integral angular lugs 11 and 12, and to the lug 11 is riveted or otherwise secured the neck 13 of a nipple 14 screwing on the threaded end 15 of a pipe 16 or other suitable lamp fixture 50 support. The upper lug 12 is provided with a tapped aperture in which screws a screw rod 20 provided at its upper end with a head 21 having an external screw thread 22 screwing into a nut or a nipple 23 forming 55 part of the usual lamp socket 24 adapted to receive and support an incandescent elec-

tric lamp 25. It will be noticed that by the arrangement described the bar 10 of the candle stand is securely fastened to the support and the screw rod 20 supporting the 60 socket 24, and the electric lamp 25 can be readily screwed up or down in the lug 12 to correspondingly lengthen or shorten the candle stand with a view to support the electric lamp 25 in the desired position relative 65 to its surrounding tubular candle body 30. After the desired adjustment is made the screw rod 20 is locked in place by a jam or lock nut 26 screwing on the screw rod 20 and abutting against the lug 12 either at the top 70 thereof or the under side, as indicated in dotted lines in Fig. 3.

It will be noticed that by providing the head 21 with the screw thread 22, the socket 24 can be readily attached in position on the 75 said head and, if necessary or desired, the nipple 23 is locked in place against accidental unscrewing by a set screw 27 screwing in the nipple 23 against the thread 22.

The candle stand shown and described is 80 very simple and durable in construction and permits minute adjustment to insure proper location of the electric lamp 25 relative to its surrounding body member.

It will also be noticed that the candle 85 stand can be readily attached to the support and the socket of the lamp can be readily attached to the candle stand.

In the modified form shown in Figs. 6 and 7, the bar 40 of the candle stand is provided at its lower end with a lug 41 on which is riveted or otherwise secured the neck 42 of a nipple 43 adapted to be attached to the lamp support. On the upper end of the bar 40 is formed a lug in the form of 90 a fork 45 engaged by a screw rod 46 adjustably fastened in place by two nuts 47 and 48 screwing against the top and bottom of the fork 45. The upper end of the screw rod 46 is provided with a threaded head 49, the same as the head 21 previously described, and adapted to screw into a nipple of a lamp socket. By the arrangement described the screw rod 46 can be readily attached to the bar and adjusted vertically thereon. 10

Having thus described my invention, I claim as new and desire to secure by Letters Patent:

1. An electric candle stand, comprising a bar provided with angular lugs, a nipple on 11 one lug and adapted to engage a fixed support, an electric lamp socket provided with

- a nipple and a screw rod screwing in the other angular lug, the screw rod having an externally threaded head screwing into the said nipple on an electric lamp socket.
5. An electric candle stand, comprising a bar provided at its upper and lower ends with integral angular lugs, of which the upper one has a tapped aperture, a nipple on the lower angular lug, a nipple on an electric lamp socket, a screw rod screwing in the said tapped aperture and provided at its upper end with a head having an external screw thread adapted to screw into the said nipple on an electric lamp socket, and means holding the said screw rod against turning.
3. An electric candle stand, comprising a bar provided at its upper and lower ends with integral angular lugs, of which the upper one has a tapped aperture, a nipple on the lower angular lug, a nipple on an electric lamp socket, a screw rod screwing in the said tapped aperture and provided at its upper end with a head having an external screw thread adapted to screw into the said nipple on an electric lamp socket, and means holding the said screw rod against turning.
- on the lower angular lug, a nipple on an electric lamp socket, a screw rod screwing in the said tapped aperture and provided at its upper end with a head having an external screw thread adapted to screw into the said nipple on an electric lamp socket, and a lock nut screwing on the said screw rod and abutting against the said upper lug.
4. An electric candle stand, comprising an electric lamp socket provided with a nipple, a bar provided at its lower end with means for attaching the bar to a fixed support, the upper end of the bar being provided with an angular lug, and a screw rod adjustably attached to the said lug and provided at its upper end with an externally threaded head screwing into the said nipple of the electric lamp socket.

LOUIS SCHLEPP.
